No. 828,940.

PATENTED AUG. 21, 1906.

W. D. LANARD.
CARBURETER.
APPLICATION FILED AUG. 27, 1904.

UNITED STATES PATENT OFFICE.

WILBUR DANIEL LANARD, OF CLEMENTON, NEW JERSEY.

CARBURETER.

No. 828,940.

Specification of Letters Patent.

Patented Aug. 21, 1906.

Application filed August 27, 1904. Serial No. 222,429.

To all whom it may concern:

Be it known that I, WILBUR DANIEL LANARD, a citizen of the United States, residing in the city of Clementon, county of Camden, 5 State of New Jersey, have invented a new and useful Carbureter, of which the following is a specification.

My invention consists of a novel construction and relation of the various parts of a 10 mixing-chamber for mixing air and the vapor of a volatile liquid.

Figure 1 is a vertical section through the axis of the mixing-chamber. Fig. 2 is a perspective view of the same. Fig. 3 is a bottom plan view. Fig. 4 is a perspective view of the sprayer which I preferably use.

Similar letters of reference indicate corresponding parts in the figures.

Referring to the drawings, I designate a 20 chamber, here shown as of cylindrical form, having the cap J, upon which chamber and cap are formed projecting cylindrical bosses open to the interior of the cylinder and in which are secured connecting pipes or tubes 25 A, C, F, G, and H. The opening between the interior O of the cylinder or mixer and connection A is reduced at M and lies below the top of the cylindrical extension N of the sprayer L. This sprayer is preferably 30 flanged and is inserted within an opening at the bottom of said cylinder from the inside thereof. The cylindrical extension is perforated at its base by a series of holes K and surrounds the conical mouthpiece or nozzle 35 E, through which air is introduced under pressure.

In operation the pipe A is connected to a reservoir otherwise closed air-tight and supplied with the desired liquid. The liquid 40 flows slowly through opening M, the volume being replaced by air through the same opening, as will be apparent, until the level B B is attained. Should any excess of liquid be withdrawn from the reservoir, it can escape 45 through the aperture at C when a cock C' is opened. Air is introduced under pressure through pipes F and G, furnishing the requisite supply for the desired mixture of gas and air and assisting in the volatilization of the 50 liquid by its passage through the same within

the cylindrical extension N. The mixture thus formed passes through the pipe H to a reservoir or point of use. As the level of the liquid falls below B B air is admitted to the liquid-reservoir and a further supply of liquid 55 withdrawn therefrom, bringing the level again to B B.

It will be evident that various changes may be made by those skilled in the art which will come within the scope of my invention, and I do not, therefore, desire to be limited in every instance to the exact construction herein shown and described.

Having thus described my invention, what I claim as new, and desire to secure by Letters Patent, is—

1. A chamber having a cap upon which are formed apertured projections, an apertured projection upon the side of the chamber, a flanged nozzle provided with a conical projection and a cylindrical extension surrounding said conical projection and provided with a plurality of apertures near the base of said extension, said nozzle being insertible within the bottom of said chamber. 75

2. The combination in a carbureter of a chamber, upon the top, bottom and sides of which are formed apertured projections, and a flanged nozzle having a conical projection and a cylindrical extension from said nozzle 80 surrounding said conical projection and provided with a plurality of apertures near the base of said extension, said nozzle being insertible in the bottom of said chamber from within. 85

3. A carbureter-reservoir for a gas-producer comprising a chamber having apertures at the top, bottom and sides thereof, a flanged nozzle insertible within said bottom aperture from the inside thereof and provided with a conical projection and a cylindrical extension from said nozzle surrounding said conical projection and provided with a plurality of apertures near the base of said extension. 90

WILBUR DANIEL LANARD.
